UNITED STATES PATENT OFFICE.

FREDERICK W. GRUNDEL, OF GYPSUM, COLORADO.

POTATO-DIGGING MACHINE.

1,333,485.

Specification of Letters Patent. Patented Mar. 9, 1920.

Application filed June 15, 1918. Serial No. 240,142.

To all whom it may concern:

Be it known that I, FREDERICK W. GRUNDEL, a citizen of the United States, residing at Gypsum, in the county of Eagle and State of Colorado, have invented certain new and useful Improvements in Potato-Digging Machines, of which the following is a specification.

This invention relates to improvements in potato digging machines and it is the principal object of the invention to provide a machine for digging and removing potatoes from the soil and then conveying the same into an assorting means whereby the potato toes can be separated and graded according to their size.

Another and equally important object of the invention is to provide the machine with means for interrupting the passage of potatoes from the conveying means to the assorting means whereby to prevent the waste of the same when the discharge chute is disaligned from the assorting means during the turning of the machine.

Other objects will be in part obvious and in part pointed out hereinafter.

The improvements in the details and arrangement of parts will be apparent from an inspection of the accompanying drawings, in connection with the specific description hereinafter contained and wherein the preferred embodiment of the invention is disclosed for the purpose of imparting a full understanding thereof.

35 In the drawings:

Figure 1 is a side elevation of the machine,

Fig. 2 is a vertical longitudinal section therethrough,

Fig. 3 is an enlarged fragmentary detail, partly in section, showing the connection between the digging machine and the assorting means,

Fig. 4 is a detail in section through the discharge chute showing the arrangement of the chute for controlling the passage of potatoes therefrom,

Fig. 5 is a top plan view of the same,

Fig. 6 is an enlarged detail, partly in section through the means for connecting the digging machine and the assorting means, and

Fig. 7 is a similar view taken at substantially right angles to the Fig. 6.

Having more particular reference to the drawings, in connection with which like

reference characters will designate corresponding parts throughout the several views, 1 represents the frame of the machine, the same, obviously, having an axle 2 arranged transversely thereof and secured to the under side of the same, on which wheels 3 are mounted for an obvious purpose. Secured to the lower end of the inclined portion of the frame 1 is an arm 4 having a draft pole, tongue or other form of draft connection 5 pivoted to its free end and carrying an adjusting lever 6, which lever has suitable connection with the drawbar 5 whereby to adjust the same vertically to vary the engagement of the digging means, hereinafter described, with the soil.

An endless conveyer 7 is arranged longitudinally of a portion of the frame 1 and as will be noted, has its opposite ends arranged about pulleys 8 journaled in bearings formed in the frame 1, said conveyer being provided with a plurality of fingers 9, which fingers serve to engage and move the potatoes removed from the soil thereonto. Rotary motion is imparted to the endless conveyer 7 by means of a sprocket chain, which as will be noted, has one end arranged about a sprocket wheel secured to the axle 2 while the remaining end is arranged about an idler sprocket wheel 5' secured to one end of a shaft journaled in bearings in the frame 1 and meshing with a sprocket wheel 8' secured to one end of the shaft carrying the pulley 8. Obviously, by interposing the idler sprocket wheel 5', the transmission of rotary motion to the pulley 8 from the sprocket chain will be reversed and consequently, the conveyer 7 will be moved in a direction such as will permit the engaging of the potatoes removed from the soil by the digging elements, hereinafter described. A second sprocket chain 10 is provided and has one end arranged about the sprocket wheel 8' while the remaining end is arranged about a sprocket wheel 13' carried on one end of the shaft journaled in suitable bearings and having connection with a substantially upright conveying means, herein-after more fully described. Supported at a point adjacent the upper or rear end of the endless conveyer 7 on a portion of the frame 1 is a trough 10, which as will be noted, receives the lower end of an endless conveyer 11 carrying a plurality of buckets 12 therein. This conveyer 11 is mounted on substantially upright sides 13 fastened at their

lower ends in a suitable manner to the adjacent portions of the sides of the frame 1 and carrying a chute 14 on the upper end thereof, whereby to receive the potatoes 5 from the buckets on the endless conveyer and direct the same into the potato assorting machine, indicated in its entirety by the numeral 15.

A plurality of digging elements 16 are 10 secured to the lower end of the inclined portion of the frame 1 and, as will be understood, serve as means for working the soil and removing the potatoes therefrom and directing the same onto the adjacent end of 15 the endless conveyer 7, whereupon they will be carried upwardly and rearwardly into the trough 10.

To regulate or control the passage of 20 potatoes from the discharge chute 14 into the potato assorting machine 15, a gate 17 is pivoted in the chute 14 at a point in proximity to the outer end thereof, carrying an apertured arm 18 on its upper marginal portion, which arm has engagement 25 with one end of a contractile spring 19, the remaining end thereof being connected to an adjacent portion of the chute 14. A connecting rod 20 is engaged with end of the shaft opposite the arm 18 and is slidably secured to the frame 1, the free end thereof being arranged at a point adjacent the driver's seat 21 of the machine and having a substantially right angularly disposed handle portion 22 formed thereon. To 30 maintain the gate 17 in its closed position with relation to the chute 14, a latch 23 is secured to the bottom of the chute and has the slideable bolt thereof arranged in an opening formed in said chute while the remaining end of the same has connection 35 with an operating rod 24 secured to the side of the frame 1 and extending to a point adjacent the operator's seat 21 whereat it is formed with a right angularly disposed handle portion 25 for an obvious purpose.

To connect the potato assorting machine with the digging machine a substantially V-shaped yoke 26 is engaged with the upper or rear end of the frame 1 and is received 40 between the rollers 27 mounted in the looped connection 28 and provided with diverging arms 29, which arms as will be noted, are secured to the sides of the assorting machine 15.

55 In operation, the digging machine is connected to a suitable draft means and is drawn over the field having the potatoes planted therein. During such movement of the machine over the field, the digging ele-

ments 16 will be engaged with the soil there- 60 of and, as will be understood, will serve to engage and remove the potatoes therefrom, these potatoes being directed rearwardly onto the endless conveyer 7 from whence they are discharged into the trough 10. At 65 this time, the potatoes are engaged by the buckets 12 carried on the endless conveyer 11 and elevated to the chute 14 from which they are discharged into the potato assorting machine 15. Should the machine be 70 turning, it is obvious that the chute 14 will be disaligned with the potato assorting machine 15 and therefore the passage of potatoes from the same to the assorting machine is discontinued by moving the gate 17 75 to its closed position. After the turn has been made and the chute 14 is again aligned with the assorting machine, the gate 17 can be reopened. Due to the connection between the digging and assorting machines, it will 80 be understood that turning of the same will be readily permitted.

Manifestly, the construction shown is capable of considerable modification and such modification as is within the scope of my 85 claim, I consider within the spirit of my invention.

I claim:

A potato harvesting machine comprising a wheeled frame having a downwardly disposed forward portion, digging elements arranged at the forward end of said portion, conveyer means in the frame and extending to a point in proximity to the rear portion of the frame, a transversely disposed trough secured to and disposed below the bottom of the rear portion of the frame, a secondary frame substantially upright on the rear portion of said first named frame, a conveyer mounted in said secondary frame and movable into said trough, a discharge chute carried by and extending from the upper end of the secondary frame, a normally closed gate pivoted for vertical movement in said chute for regulating the passage of 90 potatoes thereby into a receiving means connected to the machine, latch means extending through the bottom of said chute and engageable with the adjacent marginal portion of said gate for maintaining the same 95 locked in closed position, and means for effecting pivotal movement of the gate and for moving said latch means to released position and extended longitudinally of the frame.

In testimony whereof, I affix my signature hereto.

FREDERICK W. GRUNDEL.
